The ornamental design for a cover for tracking device as shown and described.

DESCRIPTION

FIG. 1 is a front, top, and right side perspective view of a cover for tracking device, showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a rear, top, and right side perspective view thereof;

FIG. 9 is an enlarged sectional view thereof taken in the direction of line 9-9 shown in FIG. 2; and,

FIG. 10 is a rear, top, and right side perspective view thereof in use.

The long dash short dash broken lines and arrows shown in FIG. 2 are used to identify the sectional view and form no part of the claimed design. The evenly spaced oblique parallel broken lines in FIG. 9 represent hatching lines and form no part of the claimed design. The evenly spaced broken lines shown in FIG. 10 depict environment and form no part of the claimed design.

1 Claim, 8 Drawing Sheets(56)
